L. JUDELSON

CLOTHES WRINGER

Filed April 22, 1925

Patented Nov. 6, 1928.

1,690,117

UNITED STATES PATENT OFFICE.

LOUIS JUDELSON, OF NEW YORK, N. Y.

CLOTHES WRINGER.

Application filed April 22, 1925. Serial No. 24,931.

This invention relates to clothes wringers. One object of the invention is to provide in a device of the character described improved means for safeguarding the operator from injury.

Another object of this invention is to provide in an improved device of the character described, novel means for quickly disengaging the rolls to permit easy removal of an object caught therein, and for quickly resetting the rolls to their normal operating position.

A further object of the invention is to provide a device of the character described of rugged construction and comprising few and simple parts, comparatively inexpensive to manufacture, and efficient and practical to a high degree.

Other objects of this invention will in part be obvious and in part hereinafter pointed out.

Certain features herein shown and described are shown, described and claimed in my Patent No. 1,538,993, issued May 26, 1925, and accordingly are not claimed herein.

With the above exception, the invention accordingly consists in the features of construction, combinations of elements and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a plan view of a wringer embodying the invention;

Fig. 2 is a front elevational view thereof; and

Fig. 3 is a fragmentary cross-sectional view taken on line 3-3 in Fig. 2.

Referring in detail to the drawing, 10 indicates a wringer machine consisting of upright standards 11, 11^a secured to a base 12, and a cross member 13 normally secured in position between the upper bifurcated ends 11^b of said standards, as shown in Figs. 1 and 2. The standards 11, 11^a carry the gear casings 14, 14^a in which are housed suitable gearings comprising pairs of gears indicated in dotted lines at 15, 15^a and 16, 16^a in Fig. 2. The lower gears 15, 15^a of each pair are mounted on a horizontal drive shaft 17 which in turn is journaled in bearings 18, 18^a in the standards 11, 11^a respectively. The shaft 17 at one end has an extension 17^a for coupling thereto a power drive (not shown)

of any suitable well known construction. Supported above shaft 17 is an upper shaft 19 journaled in a pair of vertically movable bearing blocks 20, 20^a, mounted over the bearings 18, 18^a in the standards 11, 11^a. The shafts 17 and 19 carry the usual wringer rolls 21 and 22 respectively.

Mounted on the front and rear sides of the gear casings 14, 14^a are brackets 23 and 23^a which are adapted to removably support a guard member 24 therebetween. Said member 24 is provided with a slotted portion 24^a to permit feeding therethrough the clothes to be wrung, the flanged sides 24^b of said member serving to prevent the accidental insertion of the operator's fingers between the rolls 21 and 22.

The bearing blocks 20 and 20^a are each recessed as at 20^b to provide seats for the lower ends of the tension springs 25, 25^a. The upper ends of said springs are preferably disposed in similar inverted recessed portions 26, 26^a preferably formed integral with the pressure end portions of a tension bar 27.

For tensioning the rolls 21, 22, pressure is applied to the bar 27 by means of any suitable adjusting means such as screw 28 which is threaded through the cross member 13 midway the ends thereof.

The means for operating the wringer rollers will now be described. Straddling the end 13^a of the cross member 13 are the keepers 30, 30^a preferably taking the form of a U. Said keepers extend downwardly over the cross member 13 and are pivotally secured as at 31, 31^a to the standards 11, 11^a. A hand lever 32 is provided which may be pivoted by means of a pin 33 to cross member 13.

This hand lever forms part of a toggle linkage comprising a pair of link arms 34, 34^a connecting the keepers 30, 30^a respectively thereto. The arm 34 is pivotally connected to the lower end of the lever 32 and is pivoted at the other end to the keeper 30. The arm 34^a is pivotally secured to the lever 32 above the pin 33 and at the other end to the keeper 30^a. As seen from Figs. 1 and 2, the end portions 13^a of the cross member 13 preferably form integral outwardly extending ramps 100 over which the keepers 30, 30^a ride as will hereinafter appear. Suitable guiding means to prevent horizontal shifting of the cross bar 13 with relation to the standard 11, 11^a may be provided as, for example, vertically 105 extending ridge projections 13^b on said bar 110 13.

The operation for separating or releasing the rolls will now be clear. When the lever 32 is in an inclined closed position, as shown in full lines in Fig. 1, the keepers 30, 30^a straddle the cross member 13 inwardly of the ramp ends 13^a, thus holding the tension bar 27 down and compressing springs 25, 25^a. The wringer rolls are then in operative position and under proper tension adjusted by screw 28. If the operator's hand or an object be caught between the rolls, he quickly strikes the hand lever 32 throwing it into open or vertical position, shown in dotted lines in Fig. 2. The link arms 34, 34^a connected to the hand lever will then push outwardly on the keepers 30, 30^a causing them to swing out of their holding position to free the ends of the bar 13, thus releasing the latter and the pressure bar 27, permitting free upward movement of the bearing blocks 20, 20^a together with the shaft 19 and roll 22 to free the hand or object caught between the rolls.

To reset the rolls 21, 22 to their effective position, the hand lever 32 is simply swung down to simultaneously restore both keepers 30, 30^a to the position for retaining the ends of the cross member 13. In said return movement of said keepers, the bight portion of the U structure is adapted to ride on the ramp ends 13^a of said member 13 whereby the latter is forced down to compress the springs 25, 25^a the desired amount.

The screw 28 provides means for adjusting the said spring compression and, when once properly set, ordinarily need not be moved except when it is desired to readjust the wringer rolls for wear.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. A wringer comprising a frame, wringer rolls carried in said frame, means for retaining said rolls in contact with each other, and means to actuate said retaining means into operative or inoperative condition, said actuating means including linkage connected to said retaining means and to said frame, and a handle forming part of the linkage to actuate the linkage.

2. A wringer comprising a frame, a pair of rolls supported therein, means for maintaining said rolls in pressure contact, a cross-bar having ramps mounted in said frame and having adjustable engagement with said maintaining means, and a single mechanism actuatable in opposite directions to release said bar from or bring said bar into operative engagement with said maintaining means by co-action with said ramps depending upon the direction of actuation. 65

3. A wringer including a frame having supporting standards, a pair of wringer rolls journaled in said standards, spring tension means for one of said rolls, said tension means including a tension bar extending between said standards, a cross bar having ramps at its ends arranged between the standards and located above the tension bar, releasable means pivotally mounted on a relatively stationary part of the wringer frame and engageable with said ramps for securing the cross bar in fixed position with respect to said frame, a single means positioned between the cross bar and tension bar for adjusting the effective pressure between the rolls, and a single means for controlling said releasable means and for resetting the tension means, the ramps on said cross bar co-acting with the releasable means to effect the resetting of the tension means on the operation of said control means. 75 80 85 90 95

4. A wringer including a frame having supporting standards, a shaft journaled in said standards and carrying a wringer roll, a second shaft arranged above the first shaft and carrying another wringer roll; spring bearings for said second shaft; a tension bar extending between said standards and having its ends bearing on said springs, an upper cross-bar arranged between the standards and located above the tension bar, inverted U-shaped members pivotally connected to the upper ends of said standards and adapted to engage an upper surface of the cross bar, an operating handle pivotally connected intermediate its ends to said cross bar, a link pivotally connected to an end of said operating handle, and having one of its ends pivotally connected to one of the U-shaped members, a second link having one of its ends pivotally connected to another of the U-shaped members, the other end of the second link being pivotally connected to the handle, ramp extension on the ends of said cross-bar, the bight portion of the U-shaped keepers being adapted to ride on said extensions when said keepers are swung into position to engage the upper surface of said cross bar. 100 105 110 115 120

In testimony whereof I affix my signature.
LOUIS JUDELSON.
